UNITED STATES PATENT OFFICE

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE

RAILWAY CAR CONSTRUCTION

Application filed January 14, 1929. Serial No. 332,326.

The device relates to railway freight cars, particularly, to that class of equipment having doors which are opened or "dropped" to discharge part or all of the lading.

The object of the invention is to provide a spreader or beam for simultaneous operation of a pair of swingable doors in a railway freight car, which spreader is operated by any of the numerous door raising mechanisms now being marketed. A further object of the invention is to provide such a spreader or beam with spaced apart portions, each of which preferably engages one of the swingable doors preferably adjacent its vertical medial line, whereby the spreader forms an equalizing lever. Any force applied by the operating mechanism adjacent the middle of the spreader is substantially equally distributed to the two doors, and furthermore, the force transmitted to one of the doors by the spreader is substantially equally distributed to the opposite vertical edges or margins of the door.

A further object of the invention is to reduce the cost and weight of the spreader and car by forming it of a casting so that the metal can be evenly distributed commensurate with the stresses.

Another object of the invention is to engage the spreader with the door adjacent a stiffening rib or ribs so that the stresses caused by the lifting of the door will not be taken by the body portion of the door.

In the drawings:

Figs. 1 to 3 show a typical application of my device to a typical railway car.

Figs. 4 to 10 show various modifications of the invention.

Figs. 1, 2 and 3 show a typical application of my invention to a typical so-called "hopper car" wherein the lower portion of the car on each side of the center sills 2 or center ridge is formed into a hopper, each hopper being provided with a swingable door 3. These doors are connected for simultaneous operation by a spreader 4 operated by a mechanism 5 connected to the middle portion thereof and positioned between the center sills and under the ridge for protection from the lading and provided with a shaft 6 extending

to opposite sides of the car for operation by a wheel 7 or wrench. There are numerous types of hopper dump cars in service on the railways with the hopper so positioned as to discharge the load between the rails and some designed to discharge the load outside of the rails and there are also so-called "general service cars" of the gondola type having flat floors comprising a plurality of hinged doors, such doors being hinged to the center construction so as to discharge the load outside of the rails. There are also dump cars used in the coke service having a floor sloping toward one side of the car with the side wall comprising a plurality of swingable doors to discharge the coke all on one side of the car. My invention is adaptable to any one of the above described cars, or in fact, to any car having two or more doors simultaneously closed by a single operative mechanism.

In the form illustrated in Figs. 1, 2 and 3 the spreader beam 4 comprises an integral casting and may be provided with a hole 8 adjacent its middle portion for reception of a part of the operating mechanism. This casting preferably comprises an eye beam section having each of its ends secured to one of the swingable doors, preferably adjacent its vertical medial line, or adjacent a vertical line 9 substantially midway between the hinge supports 10. The ends 11 of the spreader are flared out to give greater bearing area for connection to the door, and in the form illustrated, is secured thereto by rivets 12. The central portion of the spreader is offset so as not to interrupt the flange 13 on the perimeter of the door. Mechanically speaking, this spreader is a beam supported at its ends having a concentrated load at its center, therefore, by forming the spreader of a casting, the material can be distributed according to known methods for designing such a beam, thereby obtaining the maximum strength for the minimum weight of material.

Figs. 4 and 5 show a modification wherein each door is reinforced by a central rib 28 and diagonally disposed ribs 29 which extend to the corners of the door. The spreader 30 is connected to the central rib 28 of each

door. In this arrangement the force applied by the spreader to the door is distributed over substantially the entire area of the door to the flanges 31-32 adjacent the perimeter of the door.

5 Figs. 6 and 7 show a construction wherein the door is reinforced by a pair of parallel ribs 35-36 preferably positioned horizontally and connecting opposite portions of the reinforcing flanges 37 adjacent the perimeter of the door. The spreader 38 is connected to the body portion of the door between and adjacent these parallel ribs 35-36. If deemed advisable, the spreader may be provided with flanges (not shown) which could be secured to one or both of these parallel ribs.

10 Figs. 8 to 10 inclusive show a construction wherein each door is reinforced by diagonal ribs 40 extending between diagonally opposite corners of the door and terminating into or adjacent the reinforcing flanges 41 adjacent the perimeter of the door. The spreader 42 nests in and is secured to both of these diagonal ribs at their junction and also preferably to the body portion of the door by rivet 43.

15 In some cars the spreader are extended to engage locking mechanisms supported by and secured to the side of the car. A common form of locking mechanism comprises a hook which falls into place by gravity and engages the extremities of the spreader, which hook is held in place by a locking cam. 20 5 In some cars these outside locking mechanisms constitute the only means of holding the spreader and the doors in closed position. When it is desired to use such a locking mechanism I extend my spreaders, so that their 25 extremities may engage such locking mechanisms.

30 The accompanying drawings illustrate the preferred form of the invention, though it is to be understood that the invention is not limited to the exact details of construction shown and described, as it is obvious that various modifications thereof within the scope of the claims will occur to persons skilled in the art.

35 I claim:

1. In a railway car, a pair of hinged dumping doors, each having a body portion with a flange adjacent its perimeter, and a stiffener extending between opposite portions of said flange, a spreader having spaced apart portions, each portion secured to the body portion of one of said doors adjacent said stiffener, and a door operating mechanism attached to said spreader adjacent the center thereof.
2. In a railway car, a pair of hinged dumping doors, each having a body portion with a flange adjacent its perimeter, and stiffeners extending between opposite corners of the door, a spreader having spaced apart portions, each portion secured to said stiffeners

adjacent their intersection and to the body portion of the door, and a door operating mechanism attached to said spreader adjacent the center thereof.

3. In a railway car, a pair of hinged dumping doors, each having a body portion with a flange adjacent its perimeter, and a stiffener extending between opposite portions of said flange, a spreader having spaced apart portions, each portion secured to the body portion of one of said doors adjacent said stiffener.

4. In a railway car, a pair of hinged dumping doors, each having a body portion with a flange adjacent its perimeter, and stiffeners extending between opposite corners of the door, a spreader having spaced apart portions, each portion secured to said stiffeners adjacent their intersection and to the body portion of the door.
